(57) **CLAIM**

The ornamental design for an over-the-cabinet-drawer hook, as shown and described.

DESCRIPTION

FIG. 1 is a perspective view of an over-the-cabinet drawer hook in accordance with our new design;

FIG. 2 is a front elevational view thereof;

FIG. 3 is a side elevational view thereof;

FIG. 4 is a top plan view thereof;

FIG. 5 is a bottom plan view thereof; and,

FIG. 6 is a rear elevational view thereof.

The dotted-line disclosure of elements in the views is for illustrative purposes only and forms no part of the claimed design.
